F. D. BLAUVELT

ROOF FLANGE

Filed April 1, 1922

UNITED STATES PATENT OFFICE.

FREDERIC D. BLAUVELT, OF GLEN RIDGE, NEW JERSEY.

ROOF FLANGE.

Application filed April 1, 1922. Serial No. 548,706.

To all whom it may concern:

Be it known that I, FREDERIC D. BLAUVELT, a citizen of the United States, residing at Glen Ridge, in the county of Essex and State of New Jersey, have invented certain new and useful Improvements in Roof Flanges, fully described and represented in the following specification and the accompanying drawings, forming a part of the same.

This invention relates to roof flanges for making a watertight joint between a roof and a pipe projecting therethrough.

An object of the invention is to provide an improved article of this character which may be manufactured at small cost, which has the requisite strength and flexibility where needed, and which may be used upon roofs which are inclined at different angles.

A roof flange embodying the invention comprises a sheet or plate to be placed upon the roof and containing an elliptical hole, a frusto-conical boot extending upwardly from the periphery of the hole, and a flange at the upper end of the boot adapted to form a stuffing box. The flange and boot are formed of a single piece of soft metal, such as lead. This has the advantages of economy in manufacture, avoiding danger of leaks, and permitting a change in the form of the boot as well as the flange to fit on pipes at different angles to the roof-plate.

Other features and advantages of the invention are hereinafter explained in connection with a detailed description of the embodiment of the invention which is illustrated in the accompanying drawings, in which:—

Fig. 1 is a side elevation of the roof flange sectioned on the line 1—1 of Fig. 2 and showing the application of the article to a pipe extending through a roof inclined at an angle of about 22° 30'.

Fig. 2 is a plan view of the roof flange;

Fig. 3 is a fragmentary section taken on the line 1—1 of Fig. 2 and showing the form of the flange before the article is applied to a pipe;

Fig. 4 is a side elevation partly sectioned on the line 1—1 of Fig. 2 showing the application of the article to a pipe extending

through a roof inclined at an angle of 45°; and

Fig. 5 is a similar view showing the application of the article to a pipe extending through a horizontal roof.

The roof flange comprises a roof-plate 10, a frusto-conical boot 15, and a flange 20. The roof-plate 10 consists of a sheet of metal, and most desirably of sheet lead. In it is formed an elliptical hole. The portion of the plate surrounding the hole is turned up to form a lip 11.

The boot 15 and the flange 20 are formed from a single piece of soft metal. I have found lead to be the most desirable metal for this purpose. The boot and flange are best made as follows:—The lead of which they are to be formed is first forced through an orifice shaping it into a hollow cylinder having a diameter equal to that of the neck 16 of the finished article. The hollow cylinder thus formed is then rotated about its axis and pressed outwardly against an external form giving the portion of it below the neck 16 a frusto-conical shape with the sides extending most desirably at about 22½° to the principal axis of this frusto-conical portion, and the portion of it above the neck 16 an outwardly bulging shape to form the flange 20. In this operation the portion of the hollow cylinder which is formed into the flange 20 retains substantially its original thickness, while the thickness of the portion of the cylinder which is given the frusto-conical shape is decreased as its diameter is increased. The frusto-conical portion is then cut off on a plane at an angle of 90° to one of its sides to form the boot 15 of the shape shown.

The forming of the boot and flange from pressed lead as described, instead of forming it of cast metal, gives the article a number of advantages. The article may be made of uniform strength and thickness throughout any circumference, notwithstanding the fact that it may be made very thin so that only a comparatively small amount of lead is used. The decreased thickness of the boot towards its bottom gives sufficient strength to this part of the article with a minimum use of material, while the flange is thicker to have sufficient strength to permit of driving

packing against it, as hereinafter described. At the same time, while the flange is given a circular form, both the flange and the boot have sufficient flexibility to permit a modification of the shape of the flange to fit upon pipes extending at an angle to the axis of the flange and boot.

The lower edge of the boot is of such size that it fits tightly over the flange 11 surrounding the elliptical hole in the plate 10. It is placed over this flange and secured to it by welding or "burning." This may be accomplished by passing a heated tool around the lower edge of the boot. If desired, additional lead 25 may be melted against the lower edge of the boot and the surface of the plate surrounding the hole during this welding so as to give a smooth finish to the joint.

In the use of the article it is placed upon the roof with the flange 20 surrounding a pipe extending through the roof. Packing 21, such as rope oakum wound about the pipe, is then forced between the flange 20 and the pipe to make a watertight joint. The upper edge 22 of the flange may then be bent in toward or against the pipe as shown in Fig. 1 to compress the packing; or instead of bending, or flashing, the edge of the flange in over the stuffing, the stuffing may be held by the use of pitch or caulking lead. The thickness of the flange and neck is such that they have sufficient strength to permit the packing to be driven in with sufficient force to make a tight joint. At the same time the flange has sufficient flexibility to permit the bending over of its upper edge after the packing is in position.

The roof flange may be used on roofs of different inclinations. Thus, when given the shape shown in the drawing, the flange is adapted for use in connection with roofs of inclinations from 45° to horizontal. When it is used on a roof of an inclination of about $22^{\circ} 30'$, as shown in Fig. 1, the neck 16 and the flange 20 are perpendicular to the pipe so that as the neck 16 is circular it may fit

about the pipe without adjustment. When, however, the article is used on a roof inclined at more than about $22^{\circ} 30'$, as shown in Fig. 4, or on a roof inclined at less than about $22^{\circ} 30'$, as shown in Fig. 5, the neck 16 and the flange 20 must be given a somewhat elongated or elliptical shape to fit about the pipe and packing. Owing to the softness of the metal of which both the flange and the boot are made, the required elliptical shape may be given to the neck 16 and the flange 20 by merely pressing in upon opposite sides of the neck 16 and flange 20. Since the flange and the boot are formed of a single piece of soft metal, such adjustment of the shape of the flange and the upper end of the boot cannot result in any leak either at the neck 16 or elsewhere.

What is claimed is:

1. A roof flange, comprising a flat roof-plate having an elliptical hole, a frusto-conical boot extending upwardly from the edge of said hole, and an outwardly bulging flange extending from the upper edge of the boot, the flange and boot being formed of a single piece of pressed lead having its greatest thickness at the flange and gradually diminishing in thickness toward the bottom of the boot.

2. A roof flange, comprising a flat plate of soft metal having an elliptical hole, the metal around the edge of said hole being turned up to form a lip, a frusto-conical boot extending upwardly from the edge of said hole and welded to said lip, and an outwardly bulging flange extending from the upper edge of said boot, said boot and flange being formed of a single piece of soft metal.

In testimony whereof I have hereunto set my hand in the presence of two subscribing witnesses.

FREDERIC D. BLAUVELT.
